DIRECTIONAL SIGNAL UNIT FOR A VEHICLE

Lewis C. Miles, 19015 La Crosse, Lathrup Village, Mich.

Filed Apr. 14, 1960, Ser. No. 60,262

Term of patent 14 years

(Cl. D48—32)

Fig. 1.

Fig. 2.

Fig. 3.

Fig. 4.

FIGURE 1 is a side elevational view of the directional signal unit for a vehicle, according to the present invention.

FIGURE 2 is a top plan view thereof.

FIGURE 3 is an end elevational view thereof.

FIGURE 4 is a view looking at the opposite end from FIGURE 3.

The bottom of the directional signal unit is substantially flat.

I claim:

The ornamental design for a directional signal unit for a vehicle, as shown and described.
